DESIGN FOR A SEMITRAILER VEHICULAR TANK

Frederick G. Thwaits, Wauwatosa, Wis., assignor
to The Heil Co., Milwaukee, Wis., a corporation
of Wisconsin

Application November 17, 1934, Serial No. 54,056

Term of patent 14 years

To all whom it may concern:

Be it known that I, Frederick G. Thwaits, a citizen of the United States, residing at Wauwatosa, in the county of Milwaukee and State of Wisconsin, have invented a new, original, and ornamental Design for a Semitrailer Vehicular Tank, of which the following is a description, reference being had to the accompanying drawing, forming part thereof.

In the drawing:

Fig. 1 is a side elevation;

Fig. 2 is a full top view; and

Fig. 3 is a rear view, showing my new design.

The important features of the present design as distinguished from my prior design forming the subject of Design Patent No. 92,686, are the beaver-tail rear end provided with laterally rounded doors, the laterally arcuated portion at the bottom of the rear end, and the downwardly curved upper front end portion.

I claim:

The ornamental design for a semitrailer vehicular tank, substantially as shown and described.

FREDERICK G. THWAITS.
